UNITED STATES PATENT OFFICE.

JULIUS KÖNIG, OF BUDWEIS, CZECHOSLOVAKIA.

LOCK.

Application filed December 19, 1922, Serial No. 607,853, and in Czechoslovakia December 28, 1921.

It has already been proposed to make locks for right-hand and left-hand use. Such locks have a bolt with recesses for the key arranged symmetrically to the axis of the bolt and tumblers of symmetrical form. In all constructional forms known hitherto the tumblers are always under spring pressure, even when the lock is open, which causes the springs in time to lose resilience. The 10 springs are arranged either so that they are capable of being moved in the lock casing for setting the tumblers so as to coat with one or the other recess on the bolt, or they are in a spring pressed or loaded middle position, 15 which renders a special setting of the springs and tumblers before inserting the lock unnecessary, the lock being capable of being locked and opened from either of the two key holes.

One of the oldest forms of such locks is fitted with a two-armed lever for setting the double springs of the tumblers, which lever can be set from either of the two keyholes with the bolt in any position for one or the 25 other key recess in the bolt. In this arrangement the tumblers are always acted upon by the force exerted by one part of the spring or the other.

All these devices provide a more or less 30 satisfactory solution for a lock for right-hand and left-hand use, but they cannot be used for safety locks. This is made possible by the present invention, according to which in addition to a bolt with two key recesses 35 and correspondingly symmetrical tumblers an auxiliary tumbler is used, which can be displaced from a middle position, in which it is not spring loaded, from either keyhole for suitably setting the tumblers, but when 40 the bolt is in the locked position can only be swung back again on the bolt being returned into the open position by that key recess on the latter by which the closing movement of the bolt was effected. The advantage of this arrangement is that, when 45 the keyholes are suitably arranged, the lock will have the same degree of safety as certain safety locks, namely that it is impossible for instance to open the door from without, 50 when it has been locked from within.

Thus the lock used hitherto as a right-hand and left-hand lock will have a far wider field of application, since it becomes suitable for use as a safety lock.

55 In the accompanying drawings, the lock shown by way of example is a trunk lock.

Figs. 1, 2 and 3 are plan views with the side of the casing removed and the bolt in different positions, Fig. 4 shows the lock in cross-section, Figs. 5, 6 and 7 are details and 60 Fig. 8 shows a constructional form of the tumblers used.

In the example shown *a* is the bolt, which is acted on by the lock mechanism, and is guided in the front plate *b* and by the pin *c* 65 in the lock casing in the usual manner. The bolt is provided on opposite sides with driving teeth *d*, *d'*. The tumblers *e* are mounted in a known manner on the pin *c*, so that they can rotate on the same. When the bolt is in the retracted position (Fig. 1), the force otherwise exerted by the springs *f* and acting on the tumblers *e* is suspended. In order to make this force effective for bringing the tumblers *e* into the operative position, the 70 mechanism is provided with a special auxiliary tumbler *g* (Fig. 6). The latter has a V or U shaped slot formed by the longitudinal slots *h* and *h'* and the transverse slot *i*. The spring *k* of the auxiliary tumbler is not 75 under load when the bolt is in the retracted position. A pin *l* of the auxiliary tumbler engages in a slot in a two-armed lever *m*, which is pivoted on the lock casing and to the other arm of which the springs *f* of the 80 tumblers *e* are operatively connected.

Two keyholes *n* and *n'* are provided, one in the front and one in the back of the lock casing.

This mechanism acts in the following manner:

With the bolt *a* in the retracted position as shown in Fig. 1 the springs *f* and *k* exert no pressure on the tumblers *e* nor on the auxiliary tumbler *g*. The bolt is secured 95 in its position by the bolt pin *o* lying in the transverse slot *i* of the auxiliary tumbler *g*. If the key be inserted for instance from one side of the casing through the keyhole *n* and turned, first of all the auxiliary tumbler *g* 100 will be turned into the position shown in Figure 2, the double lever *m* being at the same time swung to the right, thus causing the tumblers *e* to come into the position that will allow of the subsequent movement of 105 the bolt, namely with the bolt pin *o* lying in the longitudinal slot *h* of the auxiliary tumbler *g*, whereupon the movement and locking of the bolt pin is effected in the ordinary manner by the teeth *p* of the tumblers which are spring loaded. When the 110 bolt has in this way reached its extreme pro-

jected position, it can only be returned to its retracted position shown in Fig. 1 by the lock being operated from the same side of the casing, as the key, if introduced into the keyhole n' on the other side of the casing, is not capable of turning the auxiliary tumbler g , as the latter is secured from turning about the pin e by the bolt pin o , which is in its longitudinal slot h and locked by the tumblers e . Hence for retracting the bolt the key must be introduced into the same keyhole n as that used for projecting the bolt.

The operation is similar if the bolt a has been displaced by using the keyhole n' ,

Fig. 3. In this case the double lever m is swung to the left (Fig. 3), the bolt pin o slides in the longitudinal parts h' of the slot in the auxiliary tumbler g and is locked by the teeth p' of the tumblers e .

The tumblers e and the V slot of the auxiliary tumbler g may be combined in a single part g , as shown in Fig. 8.

What I claim is:—

1. A lock having a casing having keyholes on either side, a bolt having recesses for the key on either side, tumblers having a symmetrical form, springs for setting the tumblers so as to coact with one or the other recess, a bolt pin, an auxiliary tumbler adapted to coact with the bolt pin to lock the bolt in retracted position and capable of being swung aside by the key during its bolt-projecting movement, when the latter is inserted in either of the two keyholes to permit the bolt to be slid forward, a spring for holding the auxiliary tumbler in normal intermediate position, all the tumblers being

movable to an intermediate bolt releasing position and being arranged relatively to their corresponding springs in such a manner that, when the tumblers are in their intermediate positions, they are not acted upon by the springs, and means provided on all the tumblers adapted to engage with the bolt pin to lock the bolt in projected position, said bolt pin coacting with the auxiliary tumbler to maintain the latter in such position, when the bolt is projected, as to prevent movement of the tumblers to bolt releasing position by a key inserted in any keyhole except the one used for projecting the bolt.

2. In a lock as claimed in claim 1, the provision of a U-shaped slot in the auxiliary tumbler for the purpose of holding the bolt pin in the transverse part of the U, when the lock is open, so that a movement of the bolt can only take place after the auxiliary tumbler has been swung aside, as set forth.

3. A lock as claimed in claim 1, having a lever with two arms, a slot in one arm thereof, a pin on the auxiliary tumbler for engaging in the said slot and means by which the lever is pivoted in the casing, the springs of all the tumblers with the exception of the auxiliary tumbler being arranged so as to engage the other arm of the lever in such a manner that, on the auxiliary tumbler being turned in either direction, the tumblers become spring pressed so as to operate in either direction, as set forth.

In testimony whereof I have signed my name to this specification.

DR. JULIUS KÖNIG.
